[57] CLAIM

The ornamental design for male tape for surface fastener, as shown and described.

DESCRIPTION

FIG. 1 is a top plan view of a male tape for surface fastener showing my new design;

FIG. 2 is a front elevational view thereof;

FIG. 3 is a bottom elevational view thereof;

FIG. 4 is a right side elevational view thereof;

FIG. 5 is a left side elevational view thereof;

FIG. 6 is a rear elevational view thereof;

FIG. 7 is a perspective view thereof;

FIG. 8 is a cross-sectional view taken along line A—A of FIG. 1, the broken lines showing adjacent structures are for illustrative purposes only and form no part of the claimed design; and,

FIG. 9 is a view similar to FIG. 8, showing the male tape for surface fastener in use.

FIG. 1**FIG. 2****FIG. 3****FIG. 4****FIG. 5****FIG. 6**

FIG. 7

FIG. 8

FIG. 9
